(57) CLAIM

The ornamental design for a shoe, as shown and described.

DESCRIPTION

FIG. 1 is a side photographic view of a shoe showing our new design; and,

FIG. 2 is an enlarged view of the design as shown in FIG. 1 with surrounding environment removed for clarity purposes.

The remainder of the shoe shown in a lighter grey photographic depiction forms no part of the claimed design.

1 Claim, 2 Drawing Sheets
